UNITED STATES PATENT OFFICE.

ROBERT M. COLE, OF SANDUSKY, OHIO.

PROCESS OF MAKING THYMOL FROM NITROCYMENE.

1,378,939.

Specification of Letters Patent. Patented May 24, 1921.

Application filed December 3, 1919. Serial No. 342,290.

To all whom it may concern:

Be it known that I, ROBERT M. COLE, a citizen of the United States of America, and a resident of Sandusky, county of Erie, and 5 State of Ohio, have invented certain new and useful Improvements in Processes of Making Thymol from Nitrocymene, of which the following is a specification.

The main objects of this invention are to 10 provide an improved process of obtaining thymol (1-methyl: 4-isopropyl: 5-hydroxybenzol); to provide a new and improved process of treating nitro-cymene for the purpose of obtaining thymol; and to provide 15 a process for this purpose which is simple and safe to follow and which will produce a substantial quantity of thymol at a comparatively low expense.

This new and improved process consists 20 essentially in the electrolytic reduction of nitro-cymene and the subsequent diazotization and reduction of the para-amidocymene 25 produced by electrolytic action. The electrolytic reduction is effected in the presence of sulfuric acid and the diazotization involves the use of usual stannous chlorid.

The accompanying drawing illustrates 30 diagrammatically an apparatus suitable for carrying out the electrolytic reduction.

The vessel preferably comprises a cylindrical tank 1 with a lining of lead 2, which 35 also serves as the anode. In this vessel is placed a container 3, sufficiently porous to permit the passage of ions from one chamber to another but nearly impervious to the 40 passage of molecules, and within the container is arranged a carbon or copper cathode in the form of a hollow perforated cylinder 4. Within this latter cylinder is 45 also arranged a stirrer or agitator 5, preferably made of stoneware or lead-covered iron. The anode chamber is charged with 30° Bé. (sp. gr. 1.26) sulfuric acid, and the cathode space is charged with 25° Bé. (sp. gr. 1.21) sulfuric acid. The strength of the 50 sulfuric acid in the anode space is maintained throughout the process by the addition of water which is added in suitable quantities as the reaction proceeds. The 55 nitrocymene is placed in the cathode space in a quantity approximately fifty per cent. of the weight of one hundred per cent. acid.

The electrolytic action is obtained by the use of a current density of 5½ amperes per 55 square decimeter of cathode surface, and a potential of three volts. During the process,

the temperature is maintained at between 75° and 85° C. During the electrolytic action, the nitro-cymene is kept in thorough emulsion in the aqueous acid solution by 60 means of the agitator or stirrer.

After the electrolytic action has been maintained for a suitable length of time, the contents of the vessel are allowed to cool, following which the unchanged nitro-cymene is separated for reuse, and the 1-methyl 2 amino 4 isopropyl 5 hydroxy benzol is filtered off from the remaining acid solution, which latter is strengthened for reuse. 70

The 1 methyl 2 amino 4 isopropyl 5 hydroxy benzol is then diazotized and further reduced in an alkaline solution of stannous chlorid, in the usual and well-known manner, with the resulting production of thymol. 75

The reaction taking place in following out this process may be illustrated as follows:

Although but one specific method of following out this process is herein described, it will be understood that some of the steps thereof may be altered or modified without departing from the spirit of the invention 90 as defined by the following claims.

I claim:

1. The process of making thymol which consists in the electrolytic reduction of nitro-cymene and the diazotization and reduction of the resulting 1 methyl 2 amino 4 isopropyl 5 hydroxy benzol. 95

2. The process of making thymol which consists in the electrolytic reduction of nitro-cymene in sulfuric acid, and the diazotization and reduction of the resulting 1 methyl 2 amino 4 isopropyl 5 hydroxy benzol. 100

3. The process of making thymol which consists in the electrolytic reduction of nitro-cymene in sulfuric acid the strength 105 of which in the anode and cathode chambers is substantially in the proportions of six to five respectively, and the diazotization and reduction of the resulting 1 methyl 2 amino 4 isopropyl 5 hydroxy benzol.

4. The process of making thymol which consists in the electrolytic reduction of nitro-

110

cymene in sulfuric acid, wherein the strength of the acid in the anode chamber is substantially 30% Bé. and the strength of the acid in the cathode chamber is substantially 25% Bé., and the diazotization and reduction of the resulting 1 methyl 2 amino 4 isopropyl 5 hydroxy benzol.

5. The process of making thymol which consists in the electrolytic reduction of nitro-cymene and the diazotization and reduction of the resulting 1 methyl 2 amino 4 isopropyl 5 hydroxy benzol in an alkaline solution.

10 6. The process of making thymol which consists in the electrolytic reduction of nitro-
15 cymene and the diazotization and reduction

of the resulting 1 methyl 2 amino 4 isopropyl 5 hydroxy benzol in an alkaline solution of stannous chlorid.

7. The process of making thymol which 20 consists in the electrolytic reduction of nitro-cymene in sulfuric acid, wherein the strength of the acid in the anode chamber is substantially 30% Bé. and the strength of the acid in the cathode chamber is substantially 25% Bé., and the diazotization and reduction of the resulting 1 methyl 2 amino 4 isopropyl 5 hydroxy benzol in an alkaline solution of stannous chlorid. 25

Signed at Sandusky this 29th day of November 1919.

ROBT. M. COLE.
